UNITED STATES PATENT OFFICE

2,061,646

AIR CONDITIONER

Neeta M. Belden, Wichita, Kans.

Application March 27, 1935, Serial No. 13,263

1 Claim. (Cl. 261—92)

The invention herein disclosed has reference to an air conditioner and has for its chief object to humidify and control the temperature of the air while passing therethrough, the current required may be produced mechanically or by natural draft.

A further object of my invention is to provide a rotatable device for distribution of water in such a way that the same will be evaporated by the current of air passing therethrough, humidifying the air and means to announce the exhaust of the water supply in which the device is partially submerged in its rotation for distribution of the fluid therein, preparatory for evaporation, by which means the air within a room may be properly conditioned; furthermore the distribution of disinfectant or other medicinal properties may be dispensed thereby.

A still further object of my invention is to provide a device rotatably arranged in working relation to a fluid receptacle so that the periphery of the device, being partially submerged, will convey the fluid in the receptacle for distribution upon a series of woven screen secured to each side of the device, and especially to a screen intermediately positioned with respect to the sides, for the purpose later described; furthermore the device provides for air cooling and modifying means that is accurate in its operation and inexpensive to construct and adaptable to a wide range of service.

These and other objects will hereinafter be more fully explained, reference being had to the accompanying drawing forming a part of this specification and in which like characters will apply to like parts in the different views.

Referring to the drawing:

Fig. 1 is a plan view of the device, parts removed for convenience of illustration.

Fig. 2 is a side view of the device.

Fig. 3 is an end view of Fig. 2, partly in section.

Fig. 4 contains two views of an enlarged detail of a peripheral portion of the rotor showing one of the dippers in section taken on line 4—4 in Fig. 5 the other view of the dippers being in elevation.

Fig. 5 is a cross section taken on line 5—5, Fig. 4.

Fig. 6 is a similar view to Fig. 4, except showing a modification of the fluid dispensing means to the intermediate screen.

Fig. 7 is a cross sectional view taken on line 7—7 in Fig. 6.

Fig. 8 is a reduced end view of the device and

a motor driven fan in working relation thereto.

The invention as hereinafter described, as shown in the drawing and pointed out in the claim consists of a rotor comprising a peripheral rim 1, having inwardly extending flanges 2 on each side thereof, the said flanges being L shaped in cross section, one leg snugly engaging on the outer side of the rim as shown at A, by which means the said rim is braced and capable of supporting a plurality of apertured dippers, later described. The said rim is supported by a plurality of radially positioned spokes 4, the inner ends of which are secured to a hub 5 through which a spindle 6 extends and on which the said rotor is trunnioned with an approved make of ball or roller bearings, but not shown in the drawing. The said spindle is integral with a standard 7, that is vertically positioned by bending the same at right angles to the spindle. The lower end of the standard is secured to a plate 8 having on its upper edge a returned bent portion as at B, forming a hook to engage over the upper rim of a fluid receptacle 9 by which means the rotor is supported so that the said rotor will be partially submerged in the fluid and free to rotate therein.

The end of the spindle opposite the right angle bend has an annular groove spaced from the end thereof to receive a split washer 10, frictionally secured to retain the rotor on the spindle, by which arrangement the rotor is easily removed when the said washer is withdrawn from the groove.

Secured to each side of the rotor is a woven screen 11, said screens being centrally apertured to fit snugly on their respective edge of the hub, while the outer ends of each has a bend inward as at C, forming a peripheral flange that is positioned between the outside of the said rim and leg of flange 2, adjacent thereto as shown in Figs. 40 3, 5 and 7.

Secured to the outside of each of the said screen elements is a disk 12, each disk being apertured to fit snugly and spaced a short distance from the respective end of the hub, one end of which has a cap 13, removably arranged and functioning as sealing means for its respective end of the spindle. The other end of the said spindle has a washer 14 rigidly secured and spaced from the end adjacent thereto, and between which is placed the end of an apertured arm 15, rockable on the spindle.

Secured to the outer end of the said arm is a float 16 functioning as a brake for the rotor when the fluid is practically consumed from the recep-

- tacle, in which case the downward rock of the float will wedge between its adjacent side of the rotor and a rib 17 arranged on plate 8, the said rib obliquely extending from each side of the vertical axis of the plate as shown in Fig. 2, by which arrangement the float may be turned toward either end of the receptacle for the purpose of an efficient brake for the rotor turning in either direction.
- 10 As an efficient means for distribution and evaporation of fluid carried by the rotor as it revolves, I have placed a series of screen elements 18 diagonally positioned from one edge of one of the said spokes to the opposite edge of an adjacent spoke and so on between all of the spokes. The inner edge portions of each of the said screened elements snugly engage on the hub, while the outer edge thereof, as at D, is segmental and in parallelism to the said rim and spaced therefrom as shown in Figs. 2 to 4 inclusive.
- Secured to the rim between the spokes is a dipper element 19, having a V shaped mouth as shown in Figs. 5 and 7 and converging rearward to where it joins the rim and being apertured as 25 at E along the apex line to avoid an excess load of the fluid as the dipper rises therefrom; as carried by the rotor in the direction of the arrow shown in Figs. 1 and 4, there is also arranged a tongue F extending from the apex of the mouth 30 by bending the same inward a short distance radially, with respect to the rotor and from thence outward and into the dippers, following in parallelism with the apex line a short distance, each side of the looped portion being closed to form a 35 pocket 20, said pocket having a slot 21, therein to engage on the segmental edge of its adjacent screen element 18, as bracing means at the central portion thereof, and also dispensing the fluid carried by the dipper through the medium of the 40 said dipper, and the apertures E being small and so positioned will dispense fluid slowly or cause the same to flow along the exterior in contact with the screen as the said dippers approach the horizontal plane, when the rotor is operated by a 45 motor driven fan or other source of air current, the dippers 19 will be rotated slowly thereby, successively dipping the same into the fluid, the rotation being in the direction of the arrow. Each of the dippers elevates from the receptacle a quantity of fluid, dispensing the same upon the spokes and screening therebetween through the medium of the apertures and the end portion of the spokes as they rise above a horizontal plane, at 50 which time, by reason of the tangential position 55 of the apices of the dippers, the fluid is inclined toward the mouth thereof, slowly dispensing the remainder of the fluid as they approach a vertical plane of the axis on which the rotor is trunnioned.
- 60 The outer end of the spokes at each edge is cut away for a short distance as at G, for a lesser resistance while passing through the fluid, the remaining edge portions have a slight turn to the rising side as at H, forming a trough like structure as guiding means for fluid to the hub, as the said spokes in consecutive order move upward too and past a horizontal plane, the fluid thus accumulated is free to enter the side screens.
- I am aware that the bulk of the fluid so gathered will discharge by reason of the downward angle of the spoke, but a sufficient amount of the fluid will remain by capillarity and will drain in the other direction as each spoke rises above the horizontal plane, which is controlled by the rotor.
- 70 I am also aware that a marginal portion of the

said outside screening is submerged, and will carry the fluid by capillarity and as the top of the rotor is approached, the fluid is free to pass downward by gravity. Consequently by the last two methods described for distribution of the fluid, it is intended that the entire area of all of the screen elements be moistened preparatory for evaporation when a current of air is forced through the screens by mechanical or natural means, and what is meant by mechanical means will be through the medium of a motor driven fan positioned approximately as shown in Fig. 8; and if by natural draft, the rotor may be placed in an open window or the like as an inlet vent for a room, by which means the air is made humid, and 15 disinfectant, perfume or the like may be introduced.

To cause rotation of the rotor by a current of air in parallelism or ranging direct with the axis on which the rotor turns, the said dippers spaced 20 around the inside of the rim will function as impellers owing to the slant of the sides thereof, as positioned and for which reasons the perforations E, were placed along the apex so that the air current impinging the smooth sides will be interrupted, and furthermore, the size and number of the said dippers will restrict against high velocity, as the said rotor must turn slowly and the same effect is obtained when the motor driven fan is employed. The turned edges of the spokes 25 will also function as impellers coacting with the dippers, and at all times the rotation is in the same direction until the rotor is removed and reversed on its spindle, in which case rotation will be in the opposite direction. For this reason, the said 30 float is made rockable, functioning at either side to brake against rotation when the fluid is practically exhausted, and, refilling of the container is required to continue the desired function of 35 the mechanism.

I have found by actual experience that current produced by a rotary fan is more or less spiral in its path, and for such reason, the velocity of the rotation of the rotor is increased which may not be desirable. To overcome such velocity, the said 40 rotor is reversed on its spindle reducing the angular contact of air current upon the impellers as 45 produced by the fan.

Such other modifications may be employed as lie within the scope of the appended claim. Having fully described my invention, what I claim as new and desire to secure by Letters Patent is:—

In an air conditioner of the class described, comprising a rotor having a hub, spokes and rim, also a woven wire screen for each side of the 55 rotor, an intermediate series of screens, one of each positioned between the spokes in consecutive order, the outer peripheral edge of the screens being spaced from the inside of the rim, dippers secured to the inside of the rim and centrally positioned to the spokes, a cup at the mouth of each dipper, the cup having a slot to receive the edge of the said intermediate screens respectively, each spoke having a marginal portion, each edge thereof bent obliquely to the same 60 side of the spoke forming a trough, said spoke to function as an impeller to turn the rotor, when placed in the path of a current of air, a spindle receivable by the hub and means to retain the same therein, the spindle having a right 65 angle bend where it leaves the hub, functioning as a standard, a plate to which the standard is secured and having a return bend on its edge transverse to the standard functioning as a hook, the plate having a rib oppositely extending from 70

the hook, there being one rib obliquely extending from each side of the longitudinal center of the plate, a container for fluid, the said container having four walls, the rims of which are in straight alignment from corner to corner, the said plate being adapted to seat against the inside of one of the walls and supported thereto by its return bend engaging on the adjacent rim of the wall, by which means the rotor is removable supported and positioned in working relation

to the container and partially submerged in fluid contained in the container during rotation of the rotor, a buoyant brake comprising an arm and a float, one end of the arm rockable on the spindle, the other end secured to the float, by which means, when the fluid is consumed excessively, the float will lower to engagement between the side of the rotor and rib on the plate, functioning as a brake for the rotor.
